Attorneys

UNITED STATES PATENT OFFICE.

ARTHUR F. FRATTINGER, OF SEATTLE, WASHINGTON.

SANITARY PROTECTOR FOR THE STEMS OF SMOKERS' APPLIANCES.

Application filed March 13, 1924. Serial No. 699,002.

To all whom it may concern:

Be it known that I, ARTHUR F. FRATTINGER, a citizen of the United States, residing at Seattle, in the county of King and State of Washington, have invented certain new and useful Improvements in a Sanitary Protector for the Stems of Smokers' Appliances, of which the following is a specification.

- 10 This invention relates to an improved sanitary mouth piece or protector adapted to be used upon the bit or mouth inserting ends of the stems of smokers' appliances, such as pipes and cigarette holders.
- 15 The primary object of this invention is the provision of a relatively simple and economically constructed mouth piece or protector which may receive therein the mouth inserting end of a pipe stem as a means of insuring against contact of the mouth with the stem inserting end of a pipe; the protectors being used where it is desirable to test the pipe or smoker's appliance prior to purchase of the same, and thus permitting 20 a test of the same without liability of spread of disease or contagion.

A further and important object of this invention is the provision of a mouth protector for pipes which may be sold as an 25 advertising accessory, to be used over the pipe stem when the pipe is tested with the view of purchasing the same.

A further object of this invention is the provision of a protector of the above mentioned character which may assume a receptacle form to permit insertion of a pipe stem 30 therein.

Other objects and advantages of the invention will be apparent during the course 35 of the following detailed description.

In the accompanying drawing, forming a part of this specification, and wherein similar reference characters designate corresponding parts throughout the several views

40 Figure 1 is a side elevation of the pipe, showing the bit end of the stem thereof in cross section with the improved sanitary protector.

45 Figure 2 is a plan view of the improved protector applied to the stem of a pipe or cigarette holder; this protector having as a characteristic an enclosed mouth inserting end which will not permit of drawing air through the pipe; it only being provided for

the purpose of testing the weight or balance 55 of the pipe in the mouth of the user.

Figure 3 is a plan view of a protector which may have a draft aperture in the mouth inserting end thereof to permit the user to test the resistance of a passage of 60 air through the pipe.

Figure 4 is a plan view of the blank form of the mouth piece illustrated in Figure 2.

Figure 5 is a blank form of the mouth piece illustrated in Figure 3. 65

Figure 6 is a cross sectional view taken through the mouth piece illustrated in Figure 2.

Figure 7 is a sectional view taken through the mouth piece illustrated in Figure 3. 70

Figure 8 is a transverse cross sectional view taken substantially on the line 8—8 of Figure 1, and

Figure 9 is a perspective view showing the tubular form which the mouth piece may assume for receiving the bit end of a pipe stem therein. 75

In the drawing, wherein for the purpose of illustration are shown forms of this invention which the improved protector may assume, the letter A may generally designate the type of protector which may have an enclosed mouth inserting end, while the letter B may designate the protector perforated at the mouth inserting end to permit the prospective purchaser or user to test the draft of the pipe or other tobacco user's appliance C. 80

The pipe, C or cigarette holder in which the protectors A or B may be used, of course, 85 includes the stem 12 which is provided with a draft passageway 13 therethrough open at the mouth inserting tip or bight portion of the stem 12.

The protectors A or B may be made of 90 any approved material, either flexible or rigid, although preferably the former and it may be formed of silk, fabric, pyroxyline, or wax or oil paper, although not necessarily restricted to the use of these materials. 100

For the purpose of this invention the mouth protectors A and B are formed to provide receptacles or containers which may be flexed into the tubular form illustrated in Figure 9 for insertion of the pipe stem 12, although the normal form of the protector is flat, as is illustrated in Figures 6 and 7. 105 Each of the protectors of the form A or B

includes the side flap portions 20 and 21 which are integrally connected upon a folding line 22. These flaps 20 and 21 may be of the same width, although it is preferred that 5 the flap 21 at the forward end thereof be provided with a straight marginal edge 23, whereas the flap 20 is provided with a semi-circular recess 24 extending inwardly upon the forward edge thereof. The opposite 10 ends of the flaps 20 and 21 are provided with convex marginal edges 27 and 28 respectively, struck from equal radii. The inside surface of the flap 20 adjacent the convex edge 27, and following about the convex 15 edge 27 is preferably provided with an adhesive 30. A sealing flap 32 is integrally connected at the side edge of the flap 20, opposite to the side to which the flap 21 is connected; this flap 32 being very narrow 20 and having upon the inside surface thereof a glue or adhesive 33.

The above description applies equally well to the forms A and B of the invention, and the essential difference between these 25 forms is that in the flap 21 of the form B, preferably at the center from which the marginal edge 28 is struck, the flap is perforated to provide an opening 35. The opening 35, however, is normally sealed by the 30 jagged edges of the material of the flap which extend to meet each other, as is illustrated in Figure 5 of the drawing.

In assembling the protectors the flap 21 is bent upon the folding line 22 into 35 abutting relation with the flap 20; the flaps 20 and 21 being connected at their convex marginal ends by means of the adhesive 30 to provide a flat rear end 40 substantially as is illustrated in Figure 9 of the drawing. 40 The narrow flap 32 is then bent upon its folding line over the outer surface of the flap 21, in substantially the relation illustrated in Figure 8 of the drawing, and the adhesive 33 affixes the flaps in a sealed relation to provide a protector body adapted to receive the stem of the pipe C therein.

Advertising indicia 43 may be placed upon the top flap 21 or bottom flap 20, or both flaps, substantially as is illustrated in Figure 50 3 of the drawing.

For the flexible type of protector the provision of the recess 24 in the bottom flap 20 renders the protectors easy to apply to the stem 12, since the protector can be engaged 55 by the user at the side edges thereof and by inserting the bit end of the pipe stem 12 into the recess 24, and pushing upwardly the compartment of protector may be opened and the stem 12 readily inserted therein.

60 The protector A is readily removable from the stem, and the protector A is adapted to be used for testing the balance of the pipe in the mouth of the prospective purchaser, although it is contemplated to provide a 65 puncturing tool which may be used for pro-

viding an opening at the rear or enclosed end of the receptacle or protector so that the user may have a draft for testing the resistance of a passage of air through the pipe.

70 It is to be noted that in the form of protector B the opening 35 is placed at a distance forwardly of the flat portion 40, so that the tongue of the user may engage the portion 40 and thus prevent liability of saliva entering the opening 35. The opening 35 is placed in the top flap 21 of the protector and is out of alignment with the axis of the passageway 13 of the stem.

75 From the foregoing description of this invention it is apparent that a protector has been provided which is highly desirable to be used upon the bit end of pipes which are intended for sale, so that prospective purchasers may test the same without contact with the stem. The enclosed ended protector A is chiefly desirable where it is preferred that the pipe be tested for balance only, as very often when an opening is provided the prospective purchaser would blow 80 or draw through the pipe, and unintentionally inject saliva or some germ into the passageway of the pipe stem. It is intended that a dispensing machine be used in connection with the use of the protectors; their 85 flat flexible form being chiefly desirable in that they may be compactly arranged in this dispensing machine so that the customer may remove the same without the necessity of the merchant handling them.

90 Various changes in the shape, size, and arrangement of parts may be made to the forms of invention herein shown and described, without departing from the spirit of this invention or the scope of the claims.

95 I claim:

1. A sanitary protector for the stems of smokers' appliances comprising a body formed as a receptacle provided with an open end and having one side thereof recessed inwardly from the margin at the open end to facilitate insertion of the stem into the body.

100 2. A sanitary protector for the stems of smokers' appliances comprising a body formed as a receptacle provided with an open end and having a side thereof recessed inwardly from the margin at the open end to facilitate insertion of the stem into the body, said protector at its opposite end having an opening therein normally closed but adapted to open to permit the passage of a draft therethrough incident to blowing or suction.

105 3. As an article of manufacture a flexible sanitary protector for the bit ends of smokers' pipes comprising a receptacle portion open at one end and formed to normally lie flat and entirely closed at its opposite end, said flexible sanitary protector at one side

- thereof and inwardly of the forwardly marginal edge of said side having a recess whereby to facilitate insertion of the stem end of a pipe into the protector.
5. 4. A protector of the class described comprising a pair of slide flaps folded upon each other, and a sealing flap secured to one of said flaps and folded upon the other and affixed thereto by an adhesive.
10. 5. As an article of manufacture a pipe stem mouth piece protector formed of flexible material and providing a pair of side flaps folded into abutting relation and adhered together at one end to enclose said end, and a third flap carried by one of said flaps having an adhesive thereon adapted to be folded over the other flap and adhered thereto to provide a protector receptacle having an open end.
15. 6. As an article of manufacture a protector of the class described formed in blank of a single piece of material to provide a pair of flaps of substantially the same length and width, one of said flaps at its forward end providing a straight edge and the other of said flaps at its forward end provided with an inwardly extending recess, both of said flaps at their opposite ends having convex marginal portions, a third flap formed 20 at the side of the flap having said recess therein opposite to connection of said flap with the other of said pair of flaps, said first flap having an adhesive material thereon on its inside surface, and said flap with the recess having adhesive material on the inside surface adjacent the convex marginal portion thereof.

7. As an article of manufacture a protector for pipe stems formed of top and bottom flaps connected at the sides to provide a compartment for receiving the stem of a pipe, the forward end of said protector being open and the rear end of the flaps of said container being fastened together to provide a flat portion which the tongue of a person may engage when the protector is received within the mouth.

8. As an article of manufacture a protector for pipe stems formed of top and bottom flaps connected at the sides to provide a compartment for receiving the stem of a pipe, the forward end of said protector being open and the rear end of the flaps of said container being fastened together to provide a flat portion which the tongue of a person may engage when the protector is received within the mouth and having an aperture formed in the rear end of the protector in one of the flaps thereof adjacent said flat portion.

9. A sanitary protector for the stems of smokers' appliances comprising a tubular body portion having a compartment therein and the forward end thereof open to permit the insertion of the stem of a smoker's appliance into the compartment, and a rearwardly projecting tongue engaging portion at the rear end of said tubular body portion, said tubular body portion immediately forward of said rearwardly projecting portion having an opening therethrough into the compartment.

ARTHUR F. FRATTINGER.
